UNITED STATES PATENT OFFICE.

FRANCIS MARION SHEEN, OF NEW ORLEANS, LOUISIANA.

APPARATUS FOR HANDLING PACKAGES.

Application filed January 19, 1922. Serial No. 530,364.

To all whom it may concern:

Be it known that I, FRANCIS MARION SHEEN, a citizen of the United States, residing at New Orleans, in the parish of Orleans and State of Louisiana, have invented certain new and useful Improvements in Apparatus for Handling Packages; and I do hereby declare the following to be a full, clear, and exact description of the invention, 10 such as will enable others skilled in the art to which it appertains to make and use the same.

This invention relates to an apparatus for handling packages and other articles and has 15 for its object to provide a means which will be simple in construction, comparatively inexpensive to manufacture and more efficient in use than those heretofore proposed.

With these and other objects in view the 20 invention consists in the novel details of construction and combinations of parts more fully hereinafter disclosed and particularly pointed out in the claims.

Referring to the accompanying drawings 25 forming a part of this specification in which like numerals designate like parts in all the views:—

Figure 1 is a plan view of an apparatus made in accordance with this invention; 30 Figure 2 is a side elevational view of the parts shown in Figure 1;

Figure 3 is a view similar to Figure 2 illustrating the use of the invention; and

Figure 4 is a view of one of the package 35 engaging curved members detached from the apparatus.

1 indicates a lever like member preferably made of wood which is provided with a handle portion 2 and a cutaway portion 3. Fitting 40 the cutaway portion 3 is a package engaging member 4 preferably made of metal and secured to the member 1 as by the bolts 5 and 6. Said member 4 is provided with the raised inclined portion 7 fitting the extreme end of the member 1, and said member 45 7 is provided with the arc shaped or curved member 8 adapted to fit the curvature of a barrel, hogshead or other article to be handled.

Secured as by the bolts 6 is a strap like 50 bracing member 9 having the flange 10 through which the bolt 6 passes and extending upwardly from the member 1 as shown. Said strap like member 9 is sharply bent as 55 at 11, and extends to the rear to form the

strengthening and bracing member 12 provided with the flange 13 secured to the member 1, as by the bolts 14 and 15.

Fitting in the angle formed by the bend 11 of the strap member 9 is the upright bracing 60 member 16 secured to the member 1 by any suitable means, as for example, the tenon 17 and also secured to the strap member 9 as by the bolt 18.

Fitting the said portion 12 of the strap 65 member 9 is the upper gripping member 20 provided with the rearward extension 21 secured to said portion 12 as by the bolts 22 and 23, and provided at its forward overhanging end with the curved member 24 all 70 as will be clear from Figures 1 and 2.

The operation of this device will be readily understood from the foregoing but may be briefly stated as follows:—

When it is desired to cant or move a 75 heavy object such as the hogshead 25, the upper curved member 24 is inserted in the head portion of the said hogshead so that it may fit the curvature of the chine while the lower curved member 8 is permitted to rest against 80 the outside of the hogshead as at the point illustrated at 26 in Figure 3.

Strain may now be brought on the extending handle portion 2 of the lever like member 1, whereupon the curved member 8 acting as a fulcrum, a very considerable leverage will be exerted on the hogshead 25 or other article to be handled with the result that the latter may be readily tipped or moved as in Figure 3. 90

When this strain is brought on the package being handled, the strap member 9 and bracing member 16 effectually receive said strain while the portion 12 of said strap member is longitudinally strained and therefore, resists with its maximum strength. 95

The bolts 18, 22 and 23 which secure the member 20 to the strap member 9 effectually hold the curved member 24 to said strap member 9 and thus is a rigid construction provided which has a maximum of strength and resisting power with a minimum of weight. 100

It is obvious that those skilled in the art 105 may vary the details of construction as well as the arrangement of parts without departing from the spirit of the invention, and therefore, I do not wish to be limited to the above disclosure except as may be required by the claims. 110

What is claimed is:—

1. In an apparatus for handling articles the combination of a lever member; an article engaging member rigid with said lever member; a strap member provided with an angle portion secured to said lever member; a stiffening member engaging said angle portion and said lever member; and an article engaging member rigid with said strap member, substantially as described.

2. In an apparatus for handling articles the combination of a lever member; an article engaging member of a curved form rigid with said lever member; a strap member provided with an angle portion and two flange like portions secured to said lever member; a stiffening member engaging said angle portion and said lever member; and

an article engaging member rigid with said strap member, substantially as described. 20

3. The herein described new apparatus for handling heavy packages having a curved contour comprising a lever like member; a member having an extended package engaging surface rigidly attached to said lever like member; a rigid bracing member carried by said lever like member; a strap member secured to said bracing member and lever like member and adapted to be longitudinally strained when said lever member is in use, and a package engaging member carried by said strap member, substantially as described. 25

In testimony whereof I affix my signature.

FRANCIS MARION SHEEN.
